UNITED STATES PATENT OFFICE

JOHN F. STREIB, OF AVALON, PENNSYLVANIA, ASSIGNOR TO PRESSED STEEL CAR COMPANY,
OF PITTSBURG, PENNSYLVANIA, A CORPORATION OF NEW JERSEY.

TANK-CAR.

No. 898,152.

Specification of Letters Patent. Patented Sept. 8, 1908.

Application filed February 21, 1908. Serial No. 416,991.

To all whom it may concern:

Be it known that I, JOHN F. STREIB, of Avalon, Allegheny county, Pennsylvania, a citizen of the United States, have invented 5 certain new and useful Improvements in Tank-Cars, of which the following is a full, clear, and exact description, reference being had to the accompanying drawings, in which like characters refer to like parts, and in 10 which—

Figure 1 is a general view or elevation, partly in section, of a tank car constructed in accordance with this invention; Fig. 2 is a plan view of a portion of the underframe, the 15 tank being removed; Fig. 3 is a transverse section on the line 3—3 of Fig. 2 in direction of arrow, the bottom plate of the tank being also shown; Fig. 4 is a like view in an opposite direction on the line 4—4 of Fig. 2, the 20 bottom plate of the tank being removed; Fig. 5 is a transverse section of the car through one of the bolsters of the underframe, the upper portion of the tank being removed; Fig. 5^a is a detail sectional plan of 25 end of tank saddle and bolster showing member tying or bracing saddle and bolster members together; Figs. 6 and 7 are detail views of the bolster end and tank stay tie plate forming a part of the invention, and Figs. 8, 30 9 and 10 are views similar to Figs. 2, 3 and 4, respectively, showing modifications in structure.

An object of the present invention is to provide a simple, durable and effective, as 35 well as an economical anchorage for tank cars in which the ends of the tank and car underframe are free to expand and contract independently of each other.

A further object of the present invention 40 is to provide detailed improvements in the car underframe.

Referring now in detail to the drawings, 1 represents the tank, 2 the center sills here 45 shown as having upper and lower flanges, 3 the bolsters of the car, and 1^a the bottom plate of the tank.

4 are saddles suitably formed and mounted on bolsters 3 and shaped to conform to the 50 contour of the tank 1. Saddles 4 are built-up or comprise parallel plates which are arranged in vertical alinement with vertical parallel plates forming built-up bolsters 3. The parallel plates of saddles 4 and bolsters 3 are spaced apart by, and saddles 4 and bol-

sters 3 are tied together and braced by channel or dish-shaped braces 3^a the flanges of which are riveted to webs of the plates of saddles 4 and bolsters 3. Braces 3^a may be of ordinary channel iron or may be formed by pressing. They are slightly inclined as 60 shown in Figs. 5 and 5^a.

At preferably a central location in the length of the center sills, formed by pressing or otherwise are upwardly extending integral saddle or cradle members 2^a having concave 65 upper faces which are riveted to the tank 1 or bottom plate 1^a. As shown in the drawings these saddle or cradle members 2^a are formed on the upper flange of the center sills by upward deflection of said flanges. In the 70 event of the center sills being without upper flanges said saddles or cradles would, of course, be formed by outward deflection of the sill webs.

5 are tie plates riveted to the upper surfaces or flanges of the center sills 2 and extending from points at or near each end of the car as shown in Fig. 2. Tie plates 5 are notched at their inner ends at the point where the integral saddle or cradle members 2^a are formed, so that each of the said plates extends for a distance between the integral saddle or cradle members. Each of the center sills 2 are further provided at the point where its integral saddle or cradle members 80 2^a is formed with stiffening angles 6 which is also riveted to the inwardly projecting portions of the tie plates 5.

7 is a bolster end and tank stay tie plate 85 perforated to receive one or more tank stays 90 and adapted to be riveted to end flanges of bolster diaphragms. Plates 7 are reinforced by ribs 7^a.

In Figs. 8, 9 and 10 is shown slight modifications in the center sill structure therein. 95 Angles 8 extend substantially the entire length of the center sills and abbreviated notched tie plates 9 are also provided. Stiffeners 10 and tie plates 11 are also provided to stiffen the center sill construction. 100 In other respects the structure is the same as that shown in Figs. 1 to 7, inclusive.

As is customary saddles 4 are provided with wood blocks forming a support for the tank ends which permits of contraction and 105 expansion of the tank and car frame independently of each other.

Having thus described my invention, the

following is what I claim as new therein and desire to secure by Letters Patent:

1. In a tank car, a pair of center sills having horizontal flanges deflected upwardly for a portion of their lengths to form opposing concave saddle members. 35
2. In a tank car, a pair of center sills having horizontal flanges deflected upwardly for a portion of their lengths to form opposing concave saddle members and supplemental braces for said center sills adjacent to said saddle or cradle members. 40
3. In a tank car, a pair of center sills having horizontal flanges deflected upwardly for a portion of their lengths to form opposing concave saddle members and angle plates extending along said sills beneath said saddle or cradle members. 45
4. In a tank car, a pair of center sills having horizontal flanges deflected upwardly for a portion of their lengths to form opposing concave saddle members and angle plates riveted to said center sills beneath said saddle or cradle members and a tie plate for said center sills extending between said saddle or cradle members. 50
5. In a tank car, longitudinal center sills having horizontal flanges deflected upwardly at the longitudinal center of said sills to form saddle members for the tank. 55
6. In a tank car, a pair of longitudinal sills between the car bolsters having the lon-

itudinal central portion of their upper flanges deflected to form opposing saddle members.

7. In a tank car, a pair of longitudinal sills between the car bolsters having the longitudinal central portion of their upper flanges deflected upwardly and riveted to the longitudinal central portion of the car tank. 40

8. In a tank car, a bolster comprising a pair of flanged diaphragms or plates, a ribbed or reinforced tie plate shaped to cover and tie together the outer and outer lower flanges of said diaphragms or plates. 45

9. In a tank car, a bolster comprising a pair of flanged diaphragms or plates, a tie plate shaped to cover the outer and outer lower flanges of said diaphragms or plates and perforated to receive a tank stay. 50

10. In a tank car, a bolster comprising a pair of flanged diaphragms or plates and a tank stay shaped to cover the outer and outer lower flanges of said diaphragms or plates and thickened beneath said outer lower flanges. 55

The foregoing specification signed at McKees Rocks, Allegheny county, Pennsylvania, this fourteenth day of February, 1908.

JOHN F. STREIB.
